(57) **CLAIM**

The ornamental design for mobile stand with power bank, as shown and described.

DESCRIPTION

FIG. 1 is a perspective view of mobile stand with power bank showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the design in use.

The broken lines shown in the drawings are included for the purpose of illustrating environmental structure and form no part of the claimed design.
